AUCTION RECORDING DEVICE

Anton H. Bjorlee, Welch, Minn.

Application July 13, 1935, Serial No. 31,227

2 Claims. (Cl. 129—1)

My present invention relates to improvements in recording devices and particularly to improvements in my recording device illustrated and described in my previous Patent No. 1,498,948 on 5 "Auction-sale recorders" issued June 24, 1924.

While my device disclosed in the above mentioned patent has been highly successful, it is a general object of my present invention to provide novel and useful improvements therein capable 10 of considerably increasing the ease, convenience and rapidity with which the device may be used.

An object of my invention is to provide means permitting removal of index cards from the front of my recording device.

15 Another object is to provide a movable record sheet holding and writing surface member with hand-rest means associated therewith.

Yet another object is to provide an improved index card holding means.

20 Still another object is to provide an improved duplicating record sheet and card assembly.

These and other objects and advantages of the invention will be more fully set forth in the following description made in connection with the 25 accompanying drawings, in which like reference characters refer to similar parts throughout the several views, and in which:—

Fig. 1 is a front view of my recording device;

Fig. 2 is another front view of my device with 30 parts thereof differently disposed than in Fig. 1;

Fig. 3 is a perspective view showing principally the front of the device with parts thereof disposed differently than in either Fig. 1 or Fig. 2;

Fig. 4 is a longitudinal sectional view;

Fig. 5 is a transverse sectional view taken along the line 5—5 of Fig. 2, as indicated by the arrows, 35 and drawn to a larger scale;

Fig. 6 is a transverse sectional view taken along the line 6—6 of Fig. 1, as indicated by the arrows, 40 and drawn to a larger scale;

Fig. 7 is a perspective spread-apart view of my improved duplicating sheet and card assembly, and

Fig. 8 is a perspective spread-apart view of my 45 improved index card assembly.

Referring to the drawings, my device consists in general of a casing or case C, preferably made of sheet material such as sheet metal, a plurality of duplicating record sheet and card assemblies R 50 and an index card assembly A all constructed and associated with each other as will be described.

The case C comprises a shallow rectangular pan having a bottom wall 10, longitudinal side walls 55 11, a front end wall 12, and a rear end wall 13.

The longitudinal side walls 11 and the rear end wall 13 respectively have inwardly projecting narrow flanges 11a and 13a disposed parallel to the bottom wall 10. The flanges 11a on the longitudinal side walls 11 constitute ways upon which a 5 longitudinally movable member 14 to be described may be slidably mounted.

The movable member 14 consists of a rectangular sheet or plate of material, such as metal having a width substantially equal to or preferably 10 slightly less than the width of the case C and a length substantially less than and preferably slightly over half as great as the length of the case C. The plate 14 is disposed at the upper side of the case C with its longitudinal marginal portions overlying the respective ways comprised by the flanges 11a on the longitudinal side walls of the case C. Guide strips 14a having longitudinal free portions underlying the flanges 11a are secured to the under side of the plate 14 in parallel 15 relation to and extending through substantially the forward halves of the respective longitudinal marginal portions thereof so that the flanges 11a are disposed between portions of the forward half of the plate 14 and the free portions of the respective guide strips. From the above it is obvious 20 that the plate 14 is mounted on the case C with freedom for longitudinal sliding movement with respect thereto. The plate 14 constitutes a partial top wall for the case C and its upper side 25 constitutes a base of resistance or writing surface upon which sheet material to write on may be placed. The rearward edge of the plate 14 is provided with a beaded flange 14b to serve as a finger-hold for convenience in moving the plate 14.

Means is provided on the plate 14 for holding thereon sheets of material to be written on. For this purpose rings 15 of a suitable type for holding loose-leaf sheets are secured to the plate 14 at spaced laterally aligned points substantially midway of the length of the plate 14 as shown. The rings 15 illustrated are hinged at 15a and provided with a tongue and socket joint at 15b so that the rings 15 may be opened to permit placement thereon or removal therefrom of sheets having 30 suitably spaced apertures therethrough.

A plurality of duplicating record sheet and card assemblies R, one of which is shown in Fig. 7, are placed upon the pair of rings 15 in the manner of loose leaf sheets. Each assembly R 50 consists of a card 16, a sheet 17 of carbon paper, a record sheet 18 and removable fastening means such as the gummed paper elements 19. The card 16 is of somewhat less length than the width of the plate 14 and of somewhat less width than 55

half of the length of the plate 14. The sheet 17 of carbon paper is folded once with its carboned side facing inwardly and is of such dimensions that each of the two halves thereof separated by the fold is of the same dimensions as the card 16. The card 16 is placed between the halves of the sheet 17 of carbon paper. The record sheet 18, which is of the same dimensions and is folded in the same manner as the carbon sheet 17, is placed over the carbon sheet 17 as shown. The free edges of the record sheet 18 and carbon sheet 17 are compactly placed in closely adjacent relation with each other and the card 16 and are held in such relation by the gummed paper elements 19 which are made to adhere to the outer sides of the respective free edge marginal portions of the record sheet 18. The free edge marginal portion of the above described assembly is provided with apertures 20 for the purpose of mounting the assembly on the rings 15. The outer side of the record sheet 18 is preferably suitably ruled to accommodate the written data to be entered thereon and the respective sides of the card 16 may be provided with 25 ruling similar to and registering with the ruling on the record sheet 18.

The space between the plate 14 and the bottom wall 10 of the case C contains the index card assembly A. The index card assembly consists of a plurality of rectangular index cards 21 and top and bottom cover cards 22 and 23 arranged in a stack as shown in Fig. 8. The cover cards 22 and 23 have integral rectangular anchoring tabs 22a and 23a projecting forwardly from the medial portions of their respective forward edges. A narrow strip 24 of sheet material, preferably of the same width as the anchoring tabs 22a and 23a, is disposed between each of the index cards 21 and the card next adjacent, as shown, and has a forward end portion 24a disposed between the cover card anchoring tabs 22a and 23a and serving as an anchoring element or tab for the strip 24. The stack of anchoring tabs 22a, 23a, and 24a are secured together by adhesive material, wire staples or any other suitable means to form an anchoring member. The anchoring member so formed is provided with an aperture 25. As should be apparent from the above description the index cards 21 are not secured either to the cover cards 22 and 23 or to the strips 24, but are each free for individual rearward sliding movement relative to the remaining parts of the index card assembly A.

Each of the index cards 21 is provided with a rearwardly projecting tab 21a suited for placing of identification indicia thereon and having an aperture 21b therethrough. The tabs 21a of the respective index cards 21 are not similarly located thereon but are successively staggered so that none of the tabs 21a may be hidden from view by others of the tabs 21a. The index cards 21 may be and preferably are suitably ruled to provide spaces in which written matter may be entered.

The index card assembly A described above is placed between the plate 14 and the bottom wall 10 of the case C with the free end of the anchoring member closely adjacent the forward end wall 12 of the case C and opposite marginal portions of the assembly underlying the flanges 11a on the side walls 11 of the case C. The tabs 21a of the record cards 21 project toward the rear wall 13 of the case C.

For releasably anchoring the index card assembly A in the normal position thereof de-

scribed above an anchoring pin 26 is mounted on the bottom wall 10 of the case C to project upwardly therefrom through the aperture 25 of the anchoring member of the index card assembly A.

With the plate 14 slid to its forwardmost position, the rearward edges thereof and portions of the case C define a window above the forward edge of which the tabs 21a of the index cards 21 appear as shown in Fig. 3. If it is desired to slide one of the index cards 21 from its normal position to a position wherein its major portion is accessible, the point of a pencil P may be inserted in the aperture 21b in the tab 21a of the desired card 21 whereupon the pencil P may be used to draw the card 21 rearwardly to an exposed position as shown in Fig. 2. To guide the point of a pencil P in such an operation the bottom wall 10 of the case C is so shaped as to provide a series of longitudinally extending guide grooves 10a located respectively in alignment with the various ones of the apertures 21b in the index card tabs 21a.

As previously explained, the plate 14 is free for sliding movement. Also, to make use of both sides of the record card assemblies R, the assembly R to be written on may be turned rearwardly as in Figs. 2 and 3 to expose one side and forwardly as in Fig. 1 to expose the other side. When turned rearwardly as in Figs. 2 and 3 the forward half of the plate 14 may be used as a hand-rest when writing. Means is provided for use as a hand-rest when the record card assembly to be written on is turned forwardly as in Fig. 1. To this end a hand rest plate 27 is positioned at the forward end of the top side of the case C immediately below the plate 14 so as to form in effect a forwardly projecting extension of the plate 14 when the plate 14 is positioned as shown in Fig. 1. The forward edge of the hand-rest plate 27 is connected to the upper and forward corner of the case in outwardly swingable relation thereto by means of a hinge structure 27a. To support the hand-rest plate 27 in a position as closely adjacent the lower side of the plate 14 as possible supporting pins 27b are provided mounted on and projecting downwardly from the lower side of the hand-rest plate 27 to rest at their lower ends on the bottom wall 10 of the case C. The hand-rest plate 27 is preferably made of resilient material and the pins 27b are of such length that the spring-like action of the portion of the plate 27 disposed rearwardly of the pins 27b will cause the rear edge of the plate 27 to press resiliently upwardly against the lower side of the plate 14.

Stop means is provided to normally limit movement of the plate 14. The forward edge of the plate 14 is bent downwardly and upon itself to form a rearwardly facing shoulder 14c. The medial part of the rear edge portion of the hand-rest plate 27 is slit at two points to form a rectangular tongue and this tongue is bent upwardly and then upon itself to form a forwardly facing shoulder 27c adapted for engagement with the shoulder 14c on the plate 14. Normally the plate 14 is in a position where it overlaps the hand-rest plate 27 so that the shoulders 14c and 27c face each other and constitute cooperating stop elements preventing rearward movement of the plate 14 beyond the position shown in Fig. 1. When further rearward movement of the plate 14 is desired, as for access to the index card assembly A in replacing the same, downward pressure on the rear portion of the hand-rest plate 27 will swing the shoulder 27c out of the path

of the shoulder 14c to permit such further movement.

The hinge structure 21a projects slightly above the top of the case C and serves as a stop with 5 which the forward end of the plate 14 engages to prevent forward movement of the plate 14 beyond the position thereof shown in Figs. 2 and 3.

My device is primarily intended for use in recording the transactions involved in auction sales 10 and is particularly adapted for use out of doors where wind and other weather conditions would ordinarily make the task of recording quite difficult if loose sheets, cards and carbon sheets were used. In accordance with the intended method 15 of use of my device the index card assembly A and a suitable number of duplicating record sheet and card assemblies R are prepared and placed in normal operative relation with the remaining parts of the device at a convenient time and place 20 prior to use of the device for recording.

Preferably the various record sheet and card assemblies R are consecutively numbered for 25 convenient identification and indexing and the tabs 21a of the index cards 21 are marked with the letters of the alphabet in consecutive order.

The pertinent data concerning the transactions carried on in the auction sale and the amounts involved are entered on the record sheets 18 in the order in which the transactions are carried 30 on. Each purchaser is assigned a column or space on the one of the index cards 21 identified by the letter of the alphabet corresponding to the first letter of his name and, in this column or space each transaction in which he is involved is 35 represented by writing the amount involved in the transaction and the number of the record sheet on which the data pertaining to that transaction are entered. When the auction sale is completed the total amount to be paid by each purchaser 40 may be quickly ascertained by totalling the amounts entered on the index card under the purchaser's name. At any desired time after the auction sale the duplicating record sheet and card assemblies R may be taken apart. The record 45 sheets 18 will of course bear the original entries and the record cards 16 will have on the respective sides thereof carbon copies of the entries appearing on respective halves of the record sheets 18.

From the above it should be apparent that use 50 of my device in recording does not involve the handling of any loose sheets, cards or carbon sheets. Also it should be apparent that the device may be easily and conveniently used by a person wearing gloves.

While my device has been described in connection with its use for recording transactions in auction sales it should be obvious that the device

is well adapted for use in recording data of many other types.

It is apparent that I have invented novel and useful improvements in the auction sale recorder shown in my previous Patent No. 1,498,948 greatly increasing the ease and convenience with which 5 the device may be used.

It will, of course, be understood that various changes may be made in the form, details, proportions and arrangement of the parts, without departing from the scope of my invention, which, generally stated, consists in a device capable of carrying out the objects above set forth and in the novel parts and combinations of parts disclosed and defined in the appended claims. 15

What is claimed is:—

1. A recording device comprising a shallow, open-topped case, a flat member affording a writing surface mounted on the upper portion of said case for sliding movement longitudinally thereof, 20 said member being substantially shorter than said case, means on said writing surface for holding record sheets, the space within said case behind said member being adapted for containing index cards the upper portions of which are accessible 25 when said member is in its forwardmost position, and a plate projecting rearwardly from the upper forward corner of said case in substantially the same plane as said member for association therewith as a hand rest when said member is in positions other than its forwardmost position, said plate being swingably connected at its forward edge to the upper forward corner of said case whereby said plate may be swung outwardly when 30 said member is in a rearwardly slid position to provide access to the interior of said case for placement of cards therein or removal of cards 35 therefrom.

2. A recording device comprising a shallow, open topped case, a plate affording a writing surface mounted on the upper portion of said case for sliding movement longitudinally thereof, said plate being somewhat shorter than said case, rings for holding loose-leaf sheets mounted on the outer side of said plate, the space within said case 40 behind said plate being adapted for containing record cards the upper portions of which are accessible when said plate is in its forwardmost position, a hand-rest plate hingedly connected at its forward edge to the upper forward corner of 45 said case and normally lying parallel to and immediately below said first mentioned plate so as to be at least partially exposed when said first mentioned plate is slid rearwardly and releasable means for normally limiting forward movement 50 of said first mentioned plate relative to said hand-rest plate. 55

ANTON H. BJORLEE.
